UNITED STATES PATENT OFFICE.

CARLETON RUHE, OF OLEAN, NEW YORK.

HYDROPLANE.

1,217,828.

Specification of Letters Patent. Patented Feb. 27, 1917.

Application filed March 9, 1916. Serial No. 83,141.

To all whom it may concern:

Be it known that I, CARLETON RUHE, a citizen of the United States, residing at Olean, in the county of Cattaraugus and 5 State of New York, have invented certain new and useful Improvements in Hydroplanes, of which the following is a specification.

My invention relates to improvements in 10 hydroplanes.

An important object of the invention is to so construct the hull of the hydroplane that the frictional resistance that the same encounters with the water will be reduced 15 to the minimum whereby the hydroplane can obtain a high speed.

A further object of the invention is to provide means for supplying gas or air between a portion of the hull of the hydroplane and the water, thus reducing the friction 20 between the same.

A further object of the invention is to provide a hydroplane of the above mentioned character, which is not liable to capsize, and which may be properly steered in a 25 convenient manner.

Other objects and advantages of the invention will be apparent during the course of the following description.

30 In the accompanying drawings forming a part of this specification and in which like numerals are employed to designate like parts throughout the same,

Figure 1 is a side elevation of a hydroplane embodying my invention,

35 Fig. 2 is a longitudinal sectional view taken on line 2—2 of Fig. 4,

Fig. 3 is a transverse sectional view taken on line 3—3 of Fig. 1,

40 Fig. 4 is a plan view of the machine,

Fig. 5 is an end elevation of the same, and,

Fig. 6 is a transverse sectional view taken on line 6—6 of Fig. 1.

45 In the drawings, wherein for the purpose of illustration is shown a preferred embodiment of my invention, the numeral 10 designates a hull of the boat, as a whole, which has a substantial width and is provided with a forward pointed end 11, as more clearly 50 shown in Fig. 4. The hull 10 has a forward bottom portion 12 and a rear bottom portion 13. The forward bottom portion 12 is substantially V-shaped in cross-section, and tapers downwardly, as clearly illustrated in 55 Fig. 3. The rear bottom portion 13 is offset upwardly with respect to the forward bottom

portion 12 at a point approximately equidistantly spaced from the ends of the hull 10, providing a shoulder or step 14, as shown. The rear bottom portion 13 is 60 curved in cross-section, as more clearly shown in Fig. 5, and has its concave surface arranged lowermost. This curved rear bottom portion 13 is provided at its longitudinal edges with flat portions or runners 15, 65 which are inclined downwardly longitudinally toward their rear ends, the curvature of the bottom portion 13 decreasing toward its forward end or the step 14, at which point it is substantially flat, as shown.

70 The hull 10 is provided in its top with an opening 16, receiving a suitable high power engine 17, mounted upon a frame 18 and rigidly held thereby, in place within the hull. This engine embodies a crank shaft 75 19, connected with speed increasing transmission gearing (not shown) in a gear case 20. This transmission gearing is connected with and drives a propeller shaft 21, which is slightly inclined and extends longitudinally of the hull, at the longitudinal axis thereof. The shaft 21 is journaled through a bearing 22, at its rear end, carried by a bracket 23, which is rigidly attached to the rear end of the rear bottom portion 12, as shown. Connected with the rear end of the shaft 21 is a propeller 24, as shown.

80 The numeral 25 designates a rotatable or turbine air pump, of any well known or preferred construction, preferably of the type shown and described in my co-pending application for air pumps, filed December 21, 1915, Serial No. 68,010. This turbine is mounted within the forward portion of the hull 10 and has its fan or fans driven by the propeller shaft 21.

90 It might be stated that the transmission gearing 20 is adapted to step up the speed of rotation of the engine, whereby the shaft 21 is driven at a high speed, such as 2,000 revolutions per minute. The casing of the air pump 25 has connection with suction or inlet pipes 26, carried by branch pipes 27, connected with the exhaust manifold pipe 28 of the engine 17.

95 Connected with the pump 25 are gas outlet pipes 29, which are preferably formed of flexible hose. These outlet pipes are connected with pipes 30, extending through the offset portion 14, and discharging gas beneath the bottom 13, upon opposite sides of 100 the propeller 24, as shown. It is thus apparent that this gas will form a blanket or 105 110

sheet between the bottom 13 and the water, serving to lubricate the same and reduce the friction.

The steering of the boat is accomplished by means of direction rudders 31, rigidly mounted upon vertical shafts 32, journaled through bearings 33, rigidly attached to the rear end of the hull. The upper ends of the shafts 32 have rigid connection with cranks 34, which are connected by a pitman or rod 35, which may be moved by any suitable means.

In operation, the rotation of the crank shaft 19 of the engine 17 is increased and transmitted to the propeller shaft 21, causing the propeller 24 to effect the longitudinal travel of the hydroplane. The exhaust from the engine passes through the pipes 26 into the pump 25, and is forced thereby through pipes 29, and pipes 30 into the space beneath the bottom 13. As the speed of the hydroplane increases the hull tends to rise from the water, providing a passage between the bottom 13 and the surface of the water into which the gases are forced, forming a blanket or film between the bottom portion 13 and the water.

It is to be understood that the form of my invention herewith shown and described is to be taken as a preferred example of the

same, and that various changes in the shape, size, and arrangement of parts may be resorted to without departing from the spirit of the invention or the scope of the subjoined claim.

Having thus described my invention, I claim:

A boat hull, comprising a forward bottom portion formed substantially V-shaped in vertical transverse cross-section and tapering downwardly, the V-shaped bottom portion being inclined upwardly toward its forward end, a rear bottom portion disposed in a plane above the forward bottom portion and formed curved in vertical cross-section with its concave surface arranged lowermost for providing an air passage, the edges of the curved rear bottom portion extending downwardly toward the rear end of the hull so that the rear end of the air passage is permanently open, means to introduce gas into the air passage, and propelling means for the hull.

In testimony whereof I affix my signature in presence of two witnesses.

CARLETON RUHE.
